UNITED STATES PATENT OFFICE.

HEINRICH FASSBENDER, OF CHARLOTTENBURG, AND ERICH HABANN, OF BERLIN, GERMANY, ASSIGNEES TO DEUTSCHE TELEPHONWERKE, G. M. B. H., OF BERLIN, GERMANY.

MULTIPLEX TRANSMISSION OF MESSAGES BY HIGH-FREQUENCY OSCILLATIONS.

Application filed May 3, 1921. Serial No. 466,524.

To all whom it may concern:

Be it known that we, HEINRICH FASSBENDER and ERICH HABANN, both German citizens, and residing at Charlottenburg, Germany, and Berlin, Germany, have invented certain new and useful Improvements in Multiplex Transmission of Messages by High-Frequency Oscillations (for which we have filed applications in Germany, 4th September, 1918, 28th January, 1919, and 5th September, 1919; in Switzerland, 12th February, 1919; in Sweden, 30th March, 1920, and in Holland, 29th April, 1920), of which the following is a specification.

The subject of the invention is a conductor for multiplex high frequency telephony and telegraphy of which the efficiency is increased by suiting the high frequency oscillations, which are used simultaneously, to particular sections of the conductor in such a manner that the whole conductor can accommodate along its whole length between its end stations the longest wave which can occur in working, on which wave the telegraphic or speaking currents can be superposed by known means, whilst to sections of the conductor are imparted correspondingly shorter high frequency basic oscillations for the simultaneous communication in other directions, according to the rule, that these basic oscillations (wave lengths) are in the same relation to each other as the squares of the conductor sections on which they are used. These waves also serve as carriers of the telegraphic signs or of speech.

The reception of the various messages at the end of the separate sections and at the end of the whole conductor is ensured in the known manner by tuning the receiver. The stations of the section are provided with tuned transmitting and receiving devices, which are simply connected to the section at any time, so that each tuned receiving device only receives from the conductor the particular wave intended therefor, but allows the remaining waves to pass without obstruction. A partial relative overlapping of the sections does not cause any difficulty in this instance as an intermingling of the waves does not occur.

By using the conductor in sections for multiplex purposes and arranging the frequencies according to the lengths of these sections the damping factor for all sections becomes equal or substantially equal in a simple manner without the necessity of using for this purpose amplifying devices or similar equalizing devices, although these may be used if desired. This uniform or substantially uniform damping factor on all sections, causes the clearness to be equally good on all the sections.

This is due to the following consideration. The degree of clearness depends upon the damping which the conductor possesses for the frequency used. If in fact only one frequency comes into question, the dimensions and electrical sizes of the conductor can easily be so chosen that the damping does not exceed a determined limit with a given length of conductor. It is however different for multiplex telegraphy and telephony where a number of different frequencies are used at the same time on the conductor. In this case the quotient $\frac{K}{L}$ (where K is the capacity of the conductor per centimeter, and L the self inductance of the conductor per centimeter) for every frequency n must have a different value so as to give the same value β for all conversations in the known formula for the damping exponents.

$$(1) \beta = \frac{k}{2r} \sqrt{n \frac{K}{L}}$$

(In the formula k is a constant, r the radius of the wire). Should all conversations extend over the whole conductor, only an average β would be obtained, i. e., one half of the conversation would be clearer, the other half less clear. If, as according to the present invention, the conductor is divided into sections of different lengths with different frequencies, then the following applies.

β =the damping exponent per centimeter of the conductor.

R=the ohmic resistance per centimeter of the conductor.

K=the capacity per centimeter of the conductor.

5 L = the self induction per centimeter of the conductor. As for high frequencies the losses by leakance can be neglected the following formula will apply:

$$(2) \beta = \frac{R}{2} \sqrt{\frac{K}{L}}$$

10 Further in consequence of the skin effect the following also applies:

$$(3) R = \frac{k}{r} \sqrt{n}$$

15 wherein k is a constant, r the radius of the conducting wire, n the frequency. From this follows:—

$$(4) \beta = \frac{k}{2r} \sqrt{\frac{K}{nL}}$$

20 The total damping for two conductor lengths l_1, l_2 with frequencies n_1, n_2 is therefore

$$(5) \beta_1 l_1 = \frac{kl_1}{2r} \sqrt{n_1 \frac{K}{L}}$$

$$(6) \beta_2 l_2 = \frac{kl_2}{2r} \sqrt{n_2 \frac{K}{L}}$$

30 The clearness over both conductor lengths is equally good, if the total damping in both cases is the same, i. e., when

$$(7) \beta_1 \cdot l_1 = \beta_2 \cdot l_2$$

This condition is fulfilled when

$$(8) \frac{n_1}{n_2} = \left(\frac{l_2}{l_1}\right)^2 \text{ or } \frac{\lambda_2}{\lambda_1} = \left(\frac{l_2}{l_1}\right)^2$$

as

$$(9) \frac{n_1}{n_2} = \frac{\lambda_2}{\lambda_1}$$

40 where λ_1, λ_2 are the wave lengths which correspond to the frequencies n_1, n_2 .

45 The wave lengths must be in the same ratio as the squares of the conductor sections. This ratio is theoretically correct, an approximate result would suffice in practice.

50 The damping itself may be suitably chosen (within natural limits), as the formula

$$(10) \frac{\lambda_1}{\lambda_2} = \left(\frac{l_1}{l_2}\right)^2$$

55 as will be seen is independent of the magnitude of L and K , which determine the damping. There is therefore the possibility

60 that the ratio $\frac{K}{L}$ must be so chosen, for example, that for the longest wave, therefore for the longest section, a particularly favorable value of the damping βl is obtained.

65 By approximation the quotient $\frac{K}{L}$ can however be chosen in such a manner that it produces the same damping (βl) already for

a somewhat smaller section according to the formula 5 above.

70 The practical application of the invention can be carried into effect in two ways. Either the conductor sections of various lengths, as they are given by the main communicating centres (large towns, and so forth) are arranged in series, or the whole conductor is divided into a number of sections for the different frequencies so that it 75 is provided for the highest frequency (shortest wave length) with the greatest number of sections, whilst its whole length serves for the lowest frequency (longest wave).

80 In the drawing both ways are illustrated diagrammatically.

85 Figure 1 shows a whole section A—E, which is divided into subsections A—B, B—C, C—D, D—E, by additional stations connected thereto. The stations A and E communicate with each other by the longest wave, whilst the end stations of the said subsections communicate with each other by shorter waves, which correspond to the 90 square of the length of the section. For example the stations B and C communicate with each other by a longer wave than the stations A, B or C, D or E. Between C and D is transmitted the shortest wave. A longer wave than between B and C however passes between the stations A and C, A and D, B and D, D and E. C can also communicate with E by a separate wave. In Figure 1, for example, the distances between the 100 stations are indicated in kilometers and the wave lengths, which are used on the separate sections according to the invention, are also indicated.

105 Figure 2 shows a conductor wherein the waves are arranged according to the second method of communicating sections. In this case the whole length of the conductor is divided into equal or substantially equal sections, and communication is effected for 110 example between stations E and A by first passing from A to B, then from B to C, from C to D, and finally from D to E, or vice versa, whereby the shortest wave 115 length, which is made to suit these subsections, is used. At the same time, however, a message passes from B to H over the two equal sections B—E, E—H, connected together, with a corresponding longer wave 120 length. In this case devices must be provided for effecting the automatic transmission from one to the next equal section. Between unequal sections, which is the case entirely in Figure 1, such devices must effect simultaneously a transformation of the 125 frequency. Such arrangements of both kinds can be constructed in the known manner. An undesired passage of the waves from one section to another is prevented by blocking devices also of known type.

In Figure 3, for example, is illustrated the working circuit corresponding to Figure 2, wherein the station B transmits to E over the stations C, D, the station C being a transforming station and converts the frequency n_1 on the section B, C to the lower frequency n_2 required for the section C, E. At the same time (or at another time) the station D transmits over C to A on the single section D, C, also at a frequency n_1 , on the section C, A of double the length with a lower frequency n_2 . The station B is not formed as a transforming station, but, as illustrated in the figure, simply allows the frequency n_2 to pass. Also in the first mentioned communication from B over C, D to E, the station D allows the frequency n_2 to pass. Also another communication takes place—simultaneously or at another time—from station B over C, D, E to the station H not shown, therefore over six single sections (see Fig. 2) and this in two equal jumps B, E, E, H each of the frequency n_3 , which is still lower than n_2 . In this case the station E is a transforming station without changing the frequency, whilst the stations C, D, F, G simply allow the frequency n_3 to pass.

In Figure 4 is illustrated a transforming station C. As stated above it must transform the frequency n_1 to n_2 in both directions whilst it simply allows the frequency n_3 to pass. For this purpose blocking systems Kn_1 , Kn_2 (each consisting of a condenser and a coil) are provided at the station, which are loop-resonant to the frequencies n_1 , n_2 and allow the frequency n_3 to pass, but prevent the passage of the frequency n_1 , from left to right or from right to left, or the return to the right or left of the frequencies n_2 sent left or right respectively over the systems Kn_1 , Kn_2 . The frequency n_1 from the left is received on the correspondingly tuned oscillating circuit En_1 , of which the other accessory appliances (rectifiers, amplifiers) are not shown. The oscillating energy finally energizes a relay R, which consequently operates the transmitter Sn_2 , producing the frequency n_2 and transmitting it towards the right. In this manner the blocking point for communication between B to E with a change of frequency is bridged over. Similarly the frequency n_1 coming from the right is received on the right by the tuned receiving system En_1 and the energy energizes the telephone T which in its turn transmits the signs and speech to the microphone M. The latter sets the transmitter Sn_2 to the left of the speaking position in operation, which transmits the frequency n_2 to the left from the station A.

In Figure 5 is illustrated the station E. This receives the frequency n_2 passing from the right of Figure 4 and serves as a trans-

mitting station for the frequency n_3 . The systems Kn_2 , Kn_3 are inserted for blocking both frequencies. The frequency n_2 (coming from the left) is received by the tuned receiving system En_2 and the energy, for example, is conducted to an amplifying tube V behind which the actual receiver (telephone or telegraph apparatus) above the switch u is reached. If the switch u were in another position the frequency n_2 would pass on unchanged but amplified as the energy directly energizes the transmitting system Sn_2 , which produces the frequency n_2 and transmits it to the right. Similarly the frequency n_3 coming from the left is received by a tuned receiving system En_3 and an amplifying tube V_1 , and the energy energizes the transmitter Sn_3 , which transmits the same frequency n_3 to the right to the station H (see Fig. 3).

If a conductor is provided with loading coils (Pupin coils), the coils are not placed so close together that the conductor affords a good path for the shorter waves passing therethrough, but only so close together that above all those waves, which pass through at least $\frac{3}{4}$ of the total length of the conductor, are transmitted favorably. The short waves on the other hand are transmitted well in spite of the insufficient distribution of the coils as they pass through correspondingly shorter sections. These short waves are on their part not influenced by those Pupin coils which are not adapted for their lengths as they pass around these coils by passing through the condensers.

If the conductor is composed of strands for avoiding skin effects, then according to the invention the division of the cross section of the conductor by forming strands is only carried out so far that the ohmic resistance of the strand for all waves, which pass at least through $\frac{3}{4}$ of the length of the conductor, is practically the same as for continuous current. In this manner a practical and completely effective improvement is produced at a low cost, as the strand contains a comparatively small number of wires.

Having thus described our invention what we claim as new and desire to secure by Letters Patent is:—

1. In multiplex transmission of messages by high frequency oscillations of different frequencies, a conductor divided into sections, and receiving and transmitting stations connected to the various sections, the frequencies of the waves passing through the conductor being disposed for the various sections in such a manner that the wave length used on a section and the wave length used on any one other section are proportionated to each other in the same ratio as the square of length of the former sec-

tion and the square of the length of the latter section are proportionated to each other.

2. In multiplex transmission of messages by high frequency oscillations of different frequencies, a conductor divided into sections, and receiving and transmitting stations connected to the various sections, the frequencies of the waves passing through the conductor being disposed for the various sections in such a manner that the wave length used on a section and the wave length used on any one section are proportionated to each other in the same ratio as the square of length of the former section and the square of the length of the latter section are proportionated to each other, the conductor being formed of strands, the member of which is so chosen that the ohmic resistance of the conductor due to wave frequency is practically removed for the longest waves i. e. the waves used over a distance at least equal to $\frac{3}{4}$ of the total conductor-length.
3. In multiplex transmission of messages by high frequency oscillations of different frequencies, a conductor divided into sections, and receiving and transmitting stations connected to the various sections, the frequencies of the waves passing through the conductor being disposed for the various sections in such a manner that the wave length used on a section and the wave length used on any one other section are proportionated to each other in the same ratio as the square of the length of the former section and the square of the length of the

latter section are proportionated to each other, means connected to some of the sections for automatically transferring waves of certain frequencies from one section to another and means for transforming the frequency of another part of the waves as they pass from one section to another.

4. In multiplex transmission of messages by high frequency oscillations of different frequencies, a conductor divided into sections, and receiving and transmitting stations connected to the various sections, the frequencies of the waves passing through the conductor being disposed for the various sections in such a manner that the wave length used on a section and the wave length used on any one other section are proportionated to each other in the same ratio as the square of the length of the former section and the square of the length of the latter section are proportionated to each other, loop resonant circuits tuned to certain frequencies and inserted between adjacent sections to prevent the passage of these frequencies from section to section without passing through the station which lies between these two sections, the said station being adapted to receive in one case a message in its recording apparatus and to let pass in another case the message, means being provided in the latter case for amplifying the energy of the by-passing wave and if needed for changing the frequency thereof.
